UNITED STATES PATENT OFFICE.

JAMES MCCOBB SELDEN, OF PITTSBURGH, PENNSYLVANIA, ASSIGNOR TO THE SELDEN COMPANY, OF PITTSBURGH, PENNSYLVANIA, A CORPORATION OF PENNSYLVANIA.

HEATER.

1,352,481.

Specification of Letters Patent. Patented Sept. 14, 1920.

Application filed February 12, 1918. Serial No. 216,807.

To all whom it may concern:

Be it known that I, JAMES MCCOBB SELDEN, a citizen of the United States, residing at Pittsburgh, in the county of Allegheny and State of Pennsylvania, have invented 5 certain new and useful Improvements in Heaters, of which the following is a specification.

The present invention relates more particularly to apparatus for heating air used in certain chemical processes, and the object is to provide simple and effective means whereby air or other oxygen containing gas can be highly heated, its characteristics 15 changed as desired, for example, its oxygen content reduced and the action upon it completely controlled.

In the accompanying drawings:—

Figure 1 is a vertical sectional view 20 through an embodiment of the apparatus that has proven entirely satisfactory for the purpose.

Fig. 2 is a horizontal sectional view there- 25 through, and

Fig. 3 is a cross sectional view looking toward the air and flame inlets.

Similar reference numerals designate cor- 30 responding parts in all the figures of the drawings.

In the structure disclosed, a casing is em- 35 ployed, preferably angular in cross section, and constructed to withstand a high degree of heat. To this end it preferably com- 40 prises side walls formed of a lining 4 of fire brick, an intermediate section 5 of heat insulating brick, and an outer shell 6 of red brick or corresponding material. These 45 walls are reinforced at the corners by angle irons 7 and intermediate upright braces 8, 50 the whole surrounded by tie rods 9, as clearly shown in Fig. 2. An arched top is em- 55 ployed, comprising a lining 10 of fire brick with an intermediate layer 11 of insulating brick and an outer covering 12 of red brick. 60 The top also is provided with an ingress 65 opening 13 closed by a suitable plug 14. The structure thus produces an internal 70 chamber 15.

The chamber is formed into a tortuous 75 passageway by means of a baffle wall or partition 16 extending from the bottom 17 of the chamber and tapering toward its upper end, said upper end terminating short of the 80 top. The front face of this baffle is prefer- 85 ably stepped, as shown at 18, while its rear

face 19 is preferably, though not necessarily, vertical. It will thus be observed that the internal chamber on one side of the baffle is of considerably greater area than that on the other side. Extending through the wall 60 of the casing, which is opposite the stepped face 18 of the baffle 16, is a gas inlet tube 20, the same, being in the lower part of the wall and directing the gas against the lower portion of the baffle. This gas may be delivered 65 from any suitable source in predetermined quantity. On opposite sides of the gas inlet are burners 21, preferably gas, each including an air delivery pipe 22 and a gas supply pipe 23. Any well known type 70 of burner may be employed. The burners are disposed parallel with the discharge end of the gas tube 20, and thus direct flames against the base of the baffle on opposite 75 sides of the gas supply. The two burners in the particular embodiment shown are of different sizes or capacities, and this produces convenient means for varying the amount of heat or flame delivered into the chamber. For example, if the smaller of the two is 80 operated alone, a predetermined degree of heat can be produced. If the larger is operated alone, a greater degree of heat is secured, and if the two are operated together, a still higher degree can be obtained. 85 It will be understood that any desired fuel may be utilized as a heating agent. Suitable peep holes 24 are also preferably employed, the same being located in the wall of the chamber having the burners. These peep 90 holes are so located that they will give a view of the baffle at the points where the flames impinge against the same. An outlet 95 25 for the gas and products of combustion is formed in the rear wall of the chamber 15, and therefore on the opposite side of the baffle 16 to the air inlet 20 and gas burners 21. A suitable conduit 26 is provided for carrying the heated gas to the other apparatus utilized in the process, in which said gas 100 is employed.

Briefly described the operation is as follows: Metered air, or other oxygen containing gas, is introduced through the conduit 105 20, as already explained, and the current impinges against the stepped face 18 of the baffle 16. The flames from the two burners 21 are correspondingly directed against this baffle. The consequence is that the air is quickly and highly heated as it passes over 110

the baffle with the products of combustion, and finds its escape through the port 25 and conduit 26. It is found that the air can be almost instantly heated to a high temperature, for example, to any temperature desired between 150° and 1000° C., and that the oxygen content is reduced from 20 per cent. to approximately 14 per cent. This in the processes in which it is employed, for example in certain catalytic oxidation reactions as the oxidization of naphthalene to phthalic anhydrid, produces a mixture which will not readily explode. In addition, where it is desired to pass the heated gas through substances which are being vaporized or sublimed, the lowered oxygen content of the air brought about by the products of the combustion thus increasing richness of the gas, in inert gas, in carbon dioxide, water vapor and nitrogen, is an advantage for the reason that the oxidation power of the gas is reduced and results in less destruction of material vaporized or sublimed.

From the foregoing, it is thought that the construction, operation, and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:—

1. In apparatus of the character set forth, the combination with a casing, of means for introducing an oxygen containing gas to the casing, outlet means for conducting the gas from said casing, means forming a tortuous passageway between the inlet and outlet, and means for projecting a flame into the casing to heat the gas passing therethrough between the introducing and outlet means to reduce its oxygen content.
2. In apparatus of the character set forth, the combination with a casing providing an

inclosed chamber, of means for introducing an oxygen containing gas to one portion of the chamber, outlet means for conducting the gas from another portion of said chamber, a baffle wall interposed between the inlet and outlet, and means for projecting a flame against the baffle wall in the general direction of the flow of the gas therethrough.

3. In apparatus of the character set forth, the combination with a casing providing an inclosed chamber, of a baffle in said chamber, means for directing air against one face of the baffle, and means for simultaneously projecting a flame against said baffle to heat said air.

4. In apparatus of the character set forth, the combination with a casing providing an inclosed chamber, of a baffle in said chamber, means for directing air into the chamber on one side of the baffle, and means for directing flames against said side of the baffle on opposite sides of the air directing means.

5. In apparatus of the character set forth, the combination with a casing providing an inclosed chamber, of a baffle partition extending across the chamber and having one stepped side face, means for introducing air into the chamber on the side of the baffle partition having the stepped face, means for carrying off the air from the chamber on the opposite side of the baffle partition, and means located on opposite sides of the air introducing means for directing flames against the stepped face of the baffle partition.

6. In apparatus of the character set forth, the combination with a casing, of means for introducing an oxygen-containing gas into the casing, outlet means for conducting the gas from said casing, and burners of different capacities for projecting flames into the casing.

In testimony whereof, I affix my signature in the presence of two witnesses.

JAMES MCCOBB SELDEN.
